(57) **CLAIM**

The ornamental design for a kayak, as shown and described.

DESCRIPTION

FIG. 1 is a perspective view of the kayak.

FIG. 2 is a first side elevational view of kayak.

FIG. 3 is a second side elevational view of the kayak.

FIG. 4 is a top plan view of the kayak.

FIG. 5 is a bottom plan view of the kayak.

FIG. 6 is a front elevational view of the kayak; and,

FIG. 7 is a rear elevational view of the kayak.

The broken lines represent portions of the kayak that form no part of the claim.
